DESIGN FOR A COAT

Nathan Holtzman, Brooklyn, N. Y.

Application March 13, 1947, Serial No. 137,580

Term of patent 3½ years

(Cl. D3—4)

To all whom it may concern:

Be it known that I, Nathan Holtzman, a citizen of the United States, residing at 786 Hopkinson Avenue, Brooklyn, in the county of Kings, State of New York, have invented a new, original, and ornamental Design for a Coat, of which the following is a specification, reference being had to the accompanying drawings, forming part thereof.

Fig. 1 is a front view of a coat, showing my new design as it appears when worn.

Fig. 2 is a rear view of the coat in the position specified in Fig. 1.

I claim:

The ornamental design for a coat, substantially as shown and described.

NATHAN HOLTZMAN.
